DESIGN FOR A BOTTLE LIFTER

Owen Taylor, Dallas, Tex., assignor to David H. Borger, Dallas, Tex.

Application September 18, 1944, Serial No. 115,359

Term of patent 14 years

(Cl. D44—29)

To all whom it may concern:

Be it known that I, Owen Taylor, a citizen of the United States, residing at Dallas, in the county of Dallas and State of Texas, have invented a new, original, and ornamental Design for a Bottle Lifter, of which the following is a specification, reference being had to the accompanying drawing, forming part thereof.

I claim:

The ornamental design for a bottle lifter, as shown.

OWEN TAYLOR.
